(57) CLAIM

The ornamental design for a hemmed edge artificial grass mat, as shown and described.

DESCRIPTION

FIG. 1 is a front perspective view of the hemmed edge artificial grass mat;

FIG. 2 is a bottom view of the hemmed edge artificial grass mat; and,

FIG. 3 is a front perspective view of the hemmed edge artificial grass mat with a corner thereof flipped over. The evenly dashed broken lines are used to represent portions of the artificial grass that are claimed. The artificial grass is located on a rectangular plain as shown in FIG. 1. The dotted lines are used to represent stitching that is claimed.
